UNITED STATES PATENT OFFICE.

MORRIS WOODHULL, OF DAYTON, OHIO.

DESIGN FOR A CARRIAGE-BODY.

SPECIFICATION forming part of Design No. 19,766, dated April 15, 1890.

Application filed December 4, 1889. Serial No. 332,576. Term of patent 3½ years.

To all whom it may concern:

Be it known that I, MORRIS WOODHULL, a citizen of the United States, residing at Dayton, in the county of Montgomery and State 5 of Ohio, have invented and produced a certain new and original Design for Carriages, of which the following is a specification.

My design relates especially to that class of vehicles known as "jump-seat surreys."

10 The leading features of my design consist in the outline or contour of the vehicle-body, the openings or depressions in front of the vehicle-seats, the end of the vehicle-body, the seat-arms, and top supports, which are made 15 up of a series of curves, scrolls, or sweeps in the nature of ogee curves.

15 The engraving herewith presented, which is deemed sufficient to fully illustrate my design, represents a perspective view of a vehicle 20 embodying my newly-designed carriage-body.

A and B represent the front and rear seats of the vehicle, A' and B' the openings or depressions in the side of the vehicle-body in front of said seats.

25 C is the rear top support, which is curved downwardly and forwardly and joined to the rear end of the vehicle-body, which is curved forwardly and downwardly, as shown at C', thus producing the ogee curve referred to. 30 The arm B² of the rear seat, beginning with the back B³, is curved downwardly and for-

wardly in an ogee curve and joins the depression or opening B', which is also curved downwardly and forwardly, thence upwardly and backwardly, and meets the curve of the arm 35 of the forward seat A², which is curved upwardly and backwardly, also in the nature of an ogee curve. This arm A² of the front seat is a solid arm and of substantially the same size and shape as the rear opening or depression 40 B' in the side of the vehicle, the front portion of the said arm being curved downwardly and backwardly, and the front depression A' being curved downwardly and forwardly to the bracket portion of the body, 45 thence to the dash. This combination of ogee curves presents a symmetrical contour of graceful lines.

Immediately under the rear seat I provide the body with a panel D of basket-work, which 50 adds effectiveness to the general design.

What I claim is—

The design for a vehicle-body, substantially as shown and described.

In testimony whereof I have hereunto set 55 my hand this 19th day of November, A. D. 1889.

MORRIS WOODHULL.
